Primary Examiner—T. Chase Nelson*Assistant Examiner*—Karen Acker*(74) Attorney, Agent, or Firm*—Thomas W. Ryan, III(57) **CLAIM**

The ornamental design for a merchandising package, substantially as shown and described.

DESCRIPTION

FIG. 1 is a perspective view of a merchandising package according to the invention;

FIG. 2 is the bottom plan view of the merchandising package of FIG. 1 in an unfolded position;

FIG. 3 is a right side elevational view of the merchandising package of FIG. 1;

FIG. 4 is a left side elevational view of the merchandising package of FIG. 1;

FIG. 5 is a top plan view of the merchandising package of FIG. 1;

FIG. 6 is a bottom plan view of the merchandising package of FIG. 1; and,

FIG. 7 is a rear elevational view of the merchandising package of FIG. 1 with the front elevational view being a mirror image thereof.

The broken lines in FIG. 2 represent fold and perforation lines.
